UNITED STATES PATENT OFFICE.

ANDREW L. WADDELL, OF RECTOR TOWN, VIRGINIA, ASSIGNOR OF ONE-HALF TO
ALBERT L. MOFFETT, OF PLAINS, VIRGINIA.

WRENCH.

1,098,195.

Specification of Letters Patent.

Patented May 26, 1914.

Application filed September 5, 1913. Serial No. 788,286.

To all whom it may concern:

Be it known that I, ANDREW L. WADDELL, a citizen of the United States of America, residing at Rectortown, in the county of 5 Fauquier and State of Virginia, have invented certain new and useful Improvements in Wrenches, of which the following is a specification.

This invention relates to improvements in 10 quick acting or quick adjustable wrenches and the leading object of the invention is the construction of an efficient wrench of this type which can be quickly adjusted and which will be positively locked against play 15 and accidental movement.

Another object of the invention is the provision of a quick acting or adjustable wrench with a cam lever mounted to lock the movable wrench jaw and provided with a spring 20 adapted to normally hold the lever in a slot formed in the wrench shank, the spring having a bearing at its free end against the movable jaw and the cam lever being detachable from the movable jaw to provide 25 for adjustable connection, whereby the wear on the cam of the lever can be taken care of.

A still further object of the invention is the provision of a wrench with a quick adjustable jaw and means for effecting a fine 30 adjustment of the jaw arranged to coöperate with the quick adjusting means.

With the above and other objects in view the invention embraces certain combinations, 35 constructions and arrangements of parts and elements, clearly described in the following specification and clearly illustrated in the accompanying drawings.

Figure 1 is a side elevation of my improved wrench, showing jaws with pipe gripping concave faces and a portion broken away to expose the spring. Fig. 2 is a transverse sectional view taken on line 2—2 of Fig. 1, looking in the direction of arrow. Fig. 3 is a transverse sectional view 45 taken on line 3—3 of Fig. 1, looking in the direction of arrow. Fig. 4 is an end view looking in the direction of the jaws. Fig. 5 is a perspective view of the cam lever and its spring. Fig. 6 is a detail perspective view of the jaws of the wrench and a sectional view of the shank, showing the mounting of the operating screw and the sliding arrangement of the movable jaw and flat nut gripping faces of the jaws.

Referring to the accompanying drawings 55 illustrating the preferred embodiment of the invention, 5 designates the shank of the improved wrench, the opposite sides of which shank are flat. On one end of the shank a jaw 6 is fixed, and said jaw is 60 provided with teeth 6', formed on its gripping face, near the terminal thereof, and is also provided with a nail lifting claw end 7, whereby the fixed jaw 6 may be used for lifting and removing nails. 65

On the shank 5 a second jaw 8 is slidably mounted, said jaw 8 being slidably secured on the shank by means of the usual strap 9. The movable jaw 8 is formed with gripping teeth 8', arranged in confronting position to the gripping teeth 6', and also carries a rearwardly extending projection 8^a, which serves to brace the movable jaw. The shank 5 is formed with a longitudinal groove 10, which extends from a point contiguous to the fixed jaw 6 through the rear end portion of the shank. The groove 10 is formed with a flat bottom wall 10^a and outwardly diverging side walls 10^b. 70 75

The opening 8'' in the movable jaw is 80 formed larger than the width of the shank from the lower side to the upper side thereof and between the side walls of said opening 8'' the cam 11 of the lever 12 is pivotally secured by means of the detachably fastened 85 pivot pin 13, which extends through said side walls. The cam 11 is formed with a rounded lower face 11^a and with upwardly diverging faces 11^b and parallel side faces 11^c. The diverging faces 11^b correspond in 90 inclination to the diverging faces 10^b of the shank groove, and when the cam is fully seated in the groove 10 of said shank the lower rounded face 11^a, which is perpendicular to the vertical axis of the cam, is 95 spaced from the bottom wall 10^a of said shank groove, so that the diverging faces of the cam will exert a great pressure upon the shank when force is applied to the lever 12 to move said lever toward the shank. The 100 lever 12 extends rearwardly from the cam 11 and is entirely disposed in the shank groove 10, with the exception of the rear end of said lever, which is outturned to form a finger piece 12^a, which extends outwardly 105 of the groove so that the user of the wrench can place a thumb and finger under the projecting finger piece and swing the lever cam

on its pivot, so that the cam will move away from the walls of the shank groove.

In order to effectively prevent the movable jaw from slipping on the shank when the cam is in locking position, as shown in Fig. 1, the face of the movable jaw which faces the under side of the shank is formed with projections 14, which may be in the form of teeth or incomplete threads. The 10 projections 14 are adapted to coöperate with teeth or threads 15 formed on the member 16, which is located in a longitudinal groove 17 formed in the lower side of the shank. The member 16 is preferably a screw which 15 has its forward end 16^a journaled in the rear face of the fixed jaw and its rear end 16^b journaled in the shank 5. The rear end portion of the screw or member 16 is provided with a circumscribing shoulder or enlargement 16^c, whereby said screw or member 20 may be readily rotated. The screw or member 16 extends through the opening in the movable jaw and presents to the toothed face of said jaw confronting the lower side 25 of the shank a series of teeth or projections which are adapted to mesh or interlock with the teeth or projections 14 of said movable jaw. The screw or member 16 is almost entirely inclosed or received in the groove in 30 the lower side of the shank, only a small portion of the screw or member projecting from the groove, and it is this portion which presents the series of teeth 15 to the teeth or projections 14 of the movable jaw.

35 It is obvious that the screw or member 16 may be permitted to rest in the shank groove unused or that the lever cam may be swung to unlocking position and the screw rotated so as to vary the position of the projecting 40 portion of the screw, or the threads or teeth thereof, thereby effecting a finer adjustment between the movable and fixed jaws than would be possible with a fixed set of teeth for locking the movable jaw against movement.

To quickly adjust the movable jaw the lever is moved to open or unlocking position and the jaw is then moved along the shank to the desired position when the lever is returned to locking position. The engagement of the cam with the walls of the shank groove 10 draws the teeth or projections 14 against the teeth or threads 15, thereby locking the movable jaw against movement. 50 When the cam lever is swung to unlocking position the cam is moved away from the diverging walls of the shank groove 10 and the teeth or projections 14 of the movable jaw are permitted to move away from the teeth or threads 15. The movable jaw is adapted to fit closely against the sides of the shank, yet not so closely as to bind, and the cam is adapted to slightly extend the diverging walls 10^b away from each other, thereby increasing the friction between the sides of

the shank and the movable jaw and consequently rendering the locking action more positive.

The cam 12 is formed with a plurality of pivot openings 12^a, 12^b and 12^c, which are spaced apart, so that the pivot 13 may be extended through the cam at different places or points. This arrangement is provided to take up the wear on the cam. When one place on the engaging surface of the cam 75 wears down so as to temporarily render the cam useless the pivot pin is removed and the same is inserted in one of the other openings in the cam, thus bringing into use a new engaging surface on the cam.

Normally the engagement of the cam with the shank is adapted to hold the lever in the shank groove 10, but to positively hold the lever under all conditions in said shank groove a spring 18 is provided, the rear end 80 of which is secured to the lever in any suitable manner and the forward end of which is provided with an S-curved portion 18^a, one half or the lower curved offset part 18^b of which bears against the upper side of the 85 cam 11 and the other or upper curved part 18^c of which bears against the upper wall of the opening in the movable jaw.

The shank 5 is provided with a scale 19, which may be located on either side or may 90 be formed in duplicate on the opposite sides of the shank and may be of any type. By manipulating the movable jaw on the shank the thickness or width of any bolt or nut, or other small device, may be ascertained.

The upper end of the movable jaw is disposed on a slightly lower plane than the upper claw end of the fixed jaw, so that the movable jaw will not interfere with the utility of the claw of the fixed jaw.

The rear end of the shank 5 is provided with hand protecting sections 20, which may be of wood or any other material and which are arranged so as to not obstruct the groove 10 or interfere with the rearward movement 110 of the lever. It will be seen that the movable jaw can be moved against the hand protecting or handle sections 20, so that a very large nut may be gripped between the jaws.

In the drawings I have illustrated the 115 preferred embodiment of the invention and various changes in the location, construction and arrangement of parts can be resorted to without departing from the spirit of the invention.

Having described my invention I desire to secure by Letters Patent:—

A wrench comprising a shank having a fixed jaw on one end, a groove in its under-side and a second groove in its upper side, 125 a handle on one end of the shank, a rotatable screw disposed in the first groove and journaled at one end to the fixed jaw and at the other to the handle, a movable jaw slidable on the shank, said movable jaw having an 130

opening larger than the width of the shank, the walls of the second groove of the shank diverging outwardly, a cam disposed in said opening and pivoted to movable jaw and spaced from the bottom wall of the second groove, and having inclined faces to engage the diverging walls of the second groove, a lever extending from said cam and slideable in said second shank groove, said lever having inclined faces corresponding to the walls of the groove, said movable jaw having teeth to engage the threads of the screw, and a spring secured to the lever at one end and having an S-curved portion on the other

end, said curved portion bearing against the movable jaw and the cam to hold said lever seated in the second shank groove, said cam being adapted to spread apart the walls of the second groove against the movable jaw and to move the teeth of said movable jaw into engagement with the screw.

In testimony whereof I affix my signature in presence of two witnesses.

ANDREW L. WADDELL.
